STAPLE FEED FOR FASTENER
APPLYING MACHINES

Charles E. Goodstein, New Rochelle, N. Y.

Application December 12, 1945, Serial No. 634,441

5 Claims. (Cl. 1—3)

1

This invention relates to stapling devices.

An object of this invention is to provide a stapler comprising a tubular casing and a drawer slidably mounted therein, the staples being disposed within the drawer, and the drawer containing a spring pressed pusher to feed the staples to stapling position.

Another object of this invention is to provide a stapling device of the character described, in which the drawer may be wholly drawn out of the tubular casing when it is desired to refill the drawer with staples.

Another object of this invention is to provide a stapling machine of the character described, in which the casing is transparent and the pusher is colored or opaque whereby to visually indicate the quantity of staples in the device.

Still a further object of this invention is to provide in a stapling machine of the character described, a casing formed with a longitudinal slot and a pin on the pusher projecting through the slot to indicate the amount of staples left in the device.

Still another object of this invention is to provide in a stapling device of the character described, a spring within the drawer wholly supported by the drawer and tube without the necessity of any central guide or rod, whereby to permit quick disassembling of the device in the event that a staple gets stuck, and also to permit easy cleaning and to provide for complete visibility.

Still a further object of this invention is to provide a stapling device of the character described, comprising a staple magazine and a driver holder pivoted to the magazine, and comprising a pair of side members interconnected at their forward edges by a head or button carrying a driver or plunger whereby to expose the top of the tubular drawer casing.

Yet another object of this invention is to provide a strong, rugged and durable stapling machine of the character described, which shall be relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is

shown one of the various possible illustrative embodiments of this invention,

Fig. 1 is a top plan view of a stapling device embodying the invention;

5 Fig. 2 is a cross-sectional view taken on line 2—2 of Fig. 1;

Fig. 3 is a cross-sectional view taken on line 3—3 of Fig. 2;

10 Fig. 4 is a cross-sectional view taken on line 4—4 of Fig. 2;

Fig. 5 is a front end view of the stapling device;

15 Fig. 6 is a perspective view of the tubular casing;

Fig. 7 is a perspective view of a drawer with the pusher therein;

Fig. 8 is a view similar to Fig. 2, but with the drawer partly pulled out to permit insertion of a new staple strip;

20 Fig. 9 is a side elevational view of a stapling device embodying the invention and illustrating a modified construction;

Fig. 10 is a longitudinal cross-sectional view thereof;

25 Fig. 11 is a cross-sectional view taken on line 11—11 of Fig. 10;

Fig. 12 is a cross-sectional view taken on line 12—12 of Fig. 10;

30 Fig. 13 is a side elevational view of a stapling device embodying another modified form of the invention;

Fig. 14 is a top plan view of the structure shown in Fig. 13;

35 Fig. 15 is a cross-sectional view taken on line 15—15 of Fig. 14;

Fig. 16 is a cross-sectional view taken on line 16—16 of Fig. 15;

Fig. 17 is a perspective view of the pusher used in the stapling device shown in Fig. 13;

40 Fig. 18 is a perspective view of the front end plate for the staple drawer employed in the stapling device shown in Fig. 13; and

Fig. 19 is a partial elevational detail view of a front end of the staple drawer as shown in Fig. 15.

45 Referring now in detail to the drawings, Fig. 10 designates a stapling device embodying the invention. The same comprises generally, a base 11, a staple magazine 12 pivoted thereto, and a driver holder 13 likewise pivoted to the base for pivotal movement relative to the magazine.

The base 11 comprises a flat substantially rectangular member 15, having its front, rear, and side edges bent downwardly for contacting a supporting surface. At the front end of member

15 is an opening 16. At its rear end, member 15 is formed with a pair of parallel longitudinal extending slots 17. Attached to the underside of member 15 is an anvil 18 of any suitable type, for either spreading or bending the staple legs or for both.

Attached to the rear end of member 15 is a U-shaped member 20. Member 20 comprises a bottom portion 21, and upstanding legs 22 passing through the slots 17.

The bottom portion 21 may be spot welded, riveted, or otherwise fixed to the base member 15. The arms or ears 22 are formed with horizontally aligned openings through which there extends a pivot pin 24. The pivot pin 24 may be riveted or headed at its opposite ends, as at 25.

Riveted to the upper side of the base plate 15, as by rivet 27, is a leaf spring 28 adapted to engage the underside of staple magazine 12 for keeping it normally somewhat raised above the base.

Staple magazine 12 comprises a tubular casing 30, having a bottom wall 31, a top wall 32, and side walls 33. The side walls 33 have aligned openings 33a at their rear ends through which the pivot pin 24 extends. The top wall 32 is formed with a longitudinal slot 35 terminating short of the ends of said top wall. The tube 30 may be open at both ends. The bottom wall 30 is formed adjacent its front edge 36 with a transverse slot 37 through which a staple may be driven against the anvil 18.

The top wall 32 is formed with a transverse slot 39 similar to and aligned with the slot 37. Front edge 36 of the bottom wall 31 extends beyond the front edge 40 of the top wall 32, as clearly shown in Fig. 6 of the drawing. Said side walls 33 are formed, adjacent their forward ends with notches 42 and upstanding lips 43 disposed forwardly of said notches.

Slidably mounted within the tubular casing 30 is a staple drawer 45. Said drawer comprises a bottom wall 46 and side walls 47. The bottom wall 46 slidably contacts the upper surface of bottom wall 31. The side walls 47 slidably contact the inner surface of side walls 33. The upper edges of side walls 47 substantially contact the underside of top wall 32. The bottom wall 46 is formed with an upstanding lip 50 at its forward edge. Lip 50 is of less width than the bottom wall 46, and is spaced rearwardly of the front end of side walls 47. Lip 50 may be formed by slitting the bottom wall from the front end and pressing the metal upwardly. The distance between the side edges 51 of lip 50 and the inner surface of side walls 47 should be more than the spaces necessary to permit staple legs to pass through said spaces.

It will now be understood that side walls 47 extend beyond lip 50. Extending portions 53 are formed with aligned vertical slots 54 for the purpose hereinafter appearing.

The lower ends of slots 54 register with notches 42. The upper ends of slots 54 extend above the lips 43. At the rear end of bottom wall 46 are a pair of upwardly extending short lugs 55 adjacent the side walls of the drawer, for the purpose hereinafter appearing.

Disposed between the forward ends 53 of side walls 47 and fixed thereto, is a U-shaped member 60, having a bottom wall 61 and upstanding side walls 62. Side walls 62 contact the inner surfaces of the front ends 53 of side walls 47 and may be spot welded thereto. The bottom wall 61 is in the plane of the bottom wall 46. Mem-

ber 60 is spaced from lip 50 by a distance sufficient to permit a staple to pass between said member 60 and said lip 50 thereby forming between the lip 50 and the bottom wall 61 a slot 64 which, in the operative position of the stapler, registers with slot 37. Walls 62 are formed with slots 63 registering with slots 54.

Means is provided to retain the drawer 45 in operative condition within the tubular casing 30. To this end there extends through the registering slots 54, 63, a pin 70 having enlarged heads 71 at its ends. When the stapler is in operative position, pin 70 rests in notches 42.

Attached to the upper surface of bottom wall 61, is a leaf spring 73 which engages pin 70 to retain said pin within said notches 42. To release the drawer and permit the latter to be slidably moved forwardly, it is only necessary to lift pin 70 to clear the projections or lips 43, and then the drawer may be slidably moved forwardly.

Within the drawer is a staple strip 80 comprising U-shaped staples. The staples are of such size that they will fit into the drawer and will be supported therein without any additional guides. The staples 80 have downwardly extending arms, as shown in the drawing. It will be noted that the foremost staple will straddle lip 50. For this reason the upper edge 50a of said lip is somewhat below the level of the upper edges of side walls 47.

Means is provided to press the staple strip 80 forwardly into engagement with the rear edges 62a of side walls 62. To this end there is slidably mounted within the drawer, a pusher 82. The pusher 82 comprises a block of substantially rectangular cross section slidably fitting within the drawer. The height of block 82 is substantially equal to the height of the drawer. Said block is formed in its front face with a groove 83 adapted to receive the lip 50 when there are no more staples in the drawer. Screwed into the upper surface of the block is a pin or screw 84. The screw 84 passes through the slot 35. It is formed with a head 85 disposed above the top wall 32.

Within the drawer, and between the block 82 and pivot pin 24 is a pusher spring 87. The pusher spring is so shaped as to fit within the drawer without any additional guides, thereby eliminating the necessity for a central guide rod. The spring 87 is of the coiled type and is preferably curved so that the lugs 55 of the drawer may move forwardly past the spring when the drawer is pulled out of the casing 30. The lugs 55 will contact the block to limit forward movement of the drawer. Movement of the block is limited in a forward direction by contact of the pin 84 with the forward end of the slot 35.

It will now be understood that the drawer may be pulled forwardly and the staple strip dropped into the drawer and the drawer then pushed back into the casing.

The tube and drawer may be made of transparent material and the pusher 82 of colored or opaque material, so that a person can see at any time the position of the block and determine what amount of staples are left therein. The amount of staples may also be noted by the position of the head 85 of screw 84. When the head is at the forward end of the slot 35 the machine will be in condition for refilling.

The plunger holder 13 comprises a pair of parallel side bars 90, formed with openings at its rear end through which the pivot pin 24 passes. The side bars 90 are interconnected by a top button

92. The button 92 has a top wall 93 and side walls 94, and a front wall 95. The side walls may be spot welded or otherwise attached to the side bars.

Attached to the inner surface of the front wall 95 by a rivet or in any other suitable manner, is a downwardly extending driver or plunger 97. The plunger is disposed above the slot 39 so that when the holder is pressed downwardly, the plunger will press a staple downwardly through the slots 64 and 37 against the anvil. The side walls 94 are formed with inwardly turned fingers 98. Attached to the top wall 32 is a spring 99.

The spring 99 has spaced arms 99a which are riveted or otherwise fixed to the top wall as at 100.

The arms 99a are spaced so that the slot 35 and the pin head 35 may be seen. The free end of the spring 99 engages between the fingers 98 and the top wall 93. The spring thus serves two purposes. It lifts the driver holder after the holder has been depressed and released, and it also prevents lifting the driver holder more than a predetermined extent. If desired the means for lifting the driver holder may comprise fingers 102 on the side bars 98 adapted to engage the underside of the casing 30.

In Figs. 9 to 12 there is shown a stapler 10a embodying a modified form of the invention. The stapler 10a comprises a base 110 provided at its rear end with a pair of upwardly extending apertured ears 112 carrying a horizontal transverse pivot pin 113. Pivoted on said pivot pin is a staple magazine 115. Said staple magazine 115 comprises a member 116 having a top portion 117 and downwardly extending ears 118 formed with through openings through which the pivot pin 113 extends. Welded or otherwise attached to member 116 is a holder 120 comprising a top wall 121 having downwardly and inwardly extending side guide flanges 122 providing a pair of spaced aligned guide channels 123.

The top wall 121 is formed with a longitudinal slot 124 terminating short of both ends of said top wall. One of said guide flanges 122 is formed adjacent its forward end with an opening 126. Attached to said flange is a spring latch 127 provided with a finger 128 adapted to enter the opening 126 formed in channel 123. On said latch is a knob 129 for pulling back the latch.

The holder 120 is open at its forward end as shown in the drawing. Slidably mounted on the holder is a drawer 130. Drawer 130 is open at the top. It has a bottom wall 131, upwardly extending side walls 132, and outwardly extending top flanges 133 received within the slots 123. The side walls 132 of the drawer are formed with inwardly extending portions 135 at the front end of the drawer, to form a front wall for the drawer. Extending from the wall portions 135 are forwardly extending mutually contacting tabs 136 which may be riveted together at 137 thereby forming a pull finger for pulling out the drawer as will appear hereinafter. The bottom wall 131 of the drawer is formed with a transverse slot 139 just inside of the walls 135. Said bottom wall 131 is also provided with an upwardly extending finger 140 parallel to walls 135 and spaced therefrom by little more than the thickness of a staple.

The upstanding lip or finger 140 is of less width than the drawer so that the side edges thereof are spaced from the inner surfaces of the side walls of the drawer by somewhat more than the thickness of a staple. Within the

5
6
drawer is a staple strip 142, adapted to straddle the lip 140. The leading staple contacts walls 135 and may be driven downwardly through the slot 139 as will appear hereinafter.

Within the drawer is a staple pusher 150 adapted to push against the staple strip. The pusher comprises a generally prismatic block and is formed with a groove 151 at its forward surface adapted to receive the lip 140. Screwed to the upper side of the pusher 150 is a screw 153 passing through the slot 124 and having a head 154 disposed at the upper side of the holder. Pusher 150 is formed with a longitudinal through-opening 151a. It is also formed with a collar 151b. Attached to pivot pin 113a is a rod 151c passing through opening 151a. Interposed between the pusher 150 and pivot pin 113a and received on rod 151c is a coil spring 156 adapted to press the pusher 150 forwardly. The forward end of spring 156 is received on collar 151b.

Means is provided to drive staples from the magazine 115. To this end there is pivoted on the pivot 113 a driving member 160. Said driving member comprises a pair of spaced side bars 161 formed with openings at their rear ends receiving the pivot pin 113 therethrough. Interconnecting the forward ends of the boards 161 is a knob or button 162. The button 162 has a front downwardly extending wall 163. Fixed thereto and extending downwardly therefrom is a driver or plunger 164 adapted to drive the leading staple through the slot 139. The top wall of the holder is cut away at its forward edge to receive the plunger. The plunger enters the drawer between wall 135 and lip 140. Attached to the top of the holder is a strip spring 166 engaging at its free upper end, a loop 167 on the button 162. The spring 166 raises the driver after the staple is driven.

40 The base 110 may be provided with a suitable anvil 110a for turning the legs of the staple. Interposed between the base of the staple magazine is a spring 170 to space the magazine somewhat above the base. One side flange 133 of the drawer is formed adjacent its forward and rear ends with notches 175, 176. When the drawer is in position for use within the holder, the spring finger 128 engages notch 175 to retain the drawer within the holder. When it is desired to withdraw the holder to place more staples therein, the spring latch 127 is retracted, and the drawer is pulled out. The spring finger 126 then snaps into notch 176 to keep the drawer from coming entirely out of the holder. A new staple strip 55 may then be inserted into the drawer. Thereafter the latch is again retracted and the drawer pushed back into the holder until the spring again snaps into notch 175.

In Figs. 13 to 19 there is shown a stapling device 16b embodying the invention and illustrating another modified form thereof. The stapling device 16b comprises a base 175b provided with a usual anvil 175a. At the rear end of the base are a pair of upstanding apertured ears 176a supporting a transverse pivot 177. Hinged on the pivot 177 is a member 178 which may be made of synthetic plastic material or any other suitable material. Member 178 is formed with an apertured pair of ears 179 through which the pivot pin 171 passes. Said member furthermore comprises a straight elongated portion 180 formed with a longitudinal substantially cylindrical passage 182 terminating short of the front end, but extending to the rear end of said portion 180. At the front end of opening 182 is a front wall

163. Member 180 is also formed with a vertical slot 184 coextensive and communicating with opening 182. Slot 184 extends downwardly to an undersurface 186 of said portion 180. The rear end of opening 182 is screw threaded as at 187. The slot 184 likewise extends to the rear end of member 178. Portion 180 is also formed with opposite horizontal slots 189 providing inwardly turned flanges 190 spaced beneath the undersurface 186. The inner edges of the flanges 190 are spaced from one another as shown in Fig. 16 of the drawing.

The rear end of opening 182 may be closed by a screw plug 192 as shown in Fig. 15.

One side edge 193 of portion 180 is formed with a through slot 195 communicating with groove 189 for the purpose hereinafter appearing. Attached to said side edge 193 as by screw or rivet 196, or in any other suitable manner, is a spring latch 197 formed with a finger 198 extending through the opening 195. The spring latch 197 is provided with a knob or handle 199 for the purpose hereinafter appearing.

It will now be understood that by grasping knob 199, the spring latch 197 may be retracted thereby withdrawing finger 198 from groove 189. Normally the inner end of finger 198 projects into groove 189.

Slidably mounted on portion 180 of member 178 is a drawer 200. The drawer 200 may be made of sheet metal, synthetic plastic or other suitable material. The same comprises a bottom portion 201 of inverted V-cross section. Portion 201 thus comprises downwardly and outwardly inclined walls 202. Extending upwardly from the lower ends of the walls 202 are vertical walls 203. Extending outwardly from the upper ends of walls 203 are horizontal aligned flanges 204. Flanges 204 are slidably received in the grooves 189. The side walls 203 extend somewhat beyond the forward end edges 205 of walls 202 as shown in Fig. 10. Welded or otherwise attached to the front edges 206 of said side walls is a front plate 207. Plate 207 extends up above the upper surface of the drawer 200 as at 208. It will now be understood that plate 207 is spaced from edges 205. This space should preferably be sufficiently wide to permit passage of staple 210 driven downwardly through slot 211 formed at the bottom of said space. The forward edges of portions 212 forming the junction between walls 202 and 203, are beveled downwardly and forwardly as at 213 for the purpose hereinafter appearing.

Furthermore, the inner surface of plate 207 is formed with a pair of spaced, similar curved grooves 214 in alignment with the edges 213. The purpose of grooves 213 and 214 is that if a staple has its legs bent, the inclination of said surfaces will bring the legs of the staple down to slot 211, as will be more fully explained hereinafter.

The flange 204 of member 200 which is adjacent edge 193 of member 178, is formed adjacent its forward rear ends with notches 216 and 217, respectively. When the stapler is in use, spring finger 195 engages within notch 216 to keep the drawer from sliding forwardly. However, spring latch 197 may be retracted to permit the drawer to be slidably moved forwardly until the spring finger snaps into the notch 217 to prevent the drawer from being pulled out altogether.

Mounted within drawer 200 is a strip of staples 210. The staples have crown portions at the top and downwardly extending legs. The legs lie adjacent the inner surfaces of walls 203. The

lower ends of the legs of the staples are located above portions 212 of the housing.

Means is provided to push the staple strip toward end wall 207. To this end there is slidably mounted within the drawer and member 178, a pusher 220. The pusher 220 comprises a flat horizontal portion 221 from which there extends downwardly longitudinal side flanges or legs 222. The legs 222 lie in the plane of the legs of the staples 210. The top wall 221 lies in the plane of the crown portion of the staples 210. The flanges 222 project forwardly somewhat beyond the top wall 221. The upper ends 223 of the front edges 224 of said flanges 222 are beveled upwardly and rearwardly for the purpose hereinafter appearing. Extending upwardly from the top wall 221 is a longitudinal central web 225 which passes through slot 184 of member 178. Integrally formed with the web 225 is a horizontal cup or tube 226 closed at its front end by wall 227. The tube 226 is slidable longitudinally in the cylindrical opening 182. Interposed between the plug 192 and the back wall 227 of the tube 226 and extending through passage 182 is a coil compression spring 227 which urges the pusher 220 rearwardly for pressing the staples against the inner surface of the forward end wall 207.

Means is provided to drive the staples one at a time through the slot 211. To this end there is pivoted on the pivot 177, driving member 230. The driving member 230 comprises a pair of parallel side bars 231 formed with openings through which the pivot 177 passes. Said side bars 231 are normally inclined upwardly and forwardly. They are interconnected at their forward ends by a top knob 232 attached to said bars in any suitable manner. The knob 232 is formed at its front end with a downwardly extending flange 233. Attached to wall 233 as by rivet 234, or in any other suitable manner, is a downwardly extending plunger 235 which contacts the inner surface of wall 207. Attached to the top of member 178 is a strip spring 238, which engages lugs 239 on the knob 230. The spring 238 normally raises the driver to the position shown in Fig. 15. In said position the lower end of plunger 235 is above the staples. As the knob 232 is depressed the plunger will force a staple downwardly through the space between edge 205 and the inner surface 206 and downwardly through slot 211. When there are no more staples in the drawer, the edges 224 of pusher 220 will contact the inner surface of plate 207. After the driver is depressed, the plunger blade 235 will engage the beveled surface 223 to somewhat retract the pusher.

Sometimes the staple legs are pushed forwardly or rearwardly and it will be understood that the beveled or curved edges 213, 214 will guide the legs to the slot 211.

60 A spring 240 may be attached to the base as shown in Fig. 15. Said spring engages the underside of the drawer to normally maintain the staple magazine in horizontal position.

65 It will now be understood that when the drawer is depleted of staples, the knob 199 may be pulled back and the drawer can then be pulled forwardly. The pusher will contact wall 182 to limit forward movement of said pusher. A new 70 staple strip may be inserted into the drawer. The drawer is then pushed back and the spring latch snaps into notch 216 to retain the drawer in position for use.

It will thus be seen that there is provided a device in which the several objects of this invention

are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim 10 as new and desire to secure by Letters Patent:

1. A staple magazine comprising a tubular casing, a drawer within said casing, releasable means to retain the drawer in a predetermined position within said casing, said drawer being adapted to receive a staple strip, said drawer and casing having registering slots through which a staple may be driven from the magazine, a pusher slidably mounted within said drawer for pressing the staple strip in one direction, and spring means within said drawer for pressing said pusher means on said drawer to limit the movement of the staple strip in one direction, said casing being formed with a longitudinal slot, and means on said pusher extending through said slot.

2. A staple magazine comprising a tubular casing, a drawer within said casing, releasable means to retain the drawer in a predetermined position within said casing, said drawer being adapted to receive a staple strip, said drawer and casing having registering slots through which a staple may be driven from the magazine, a pusher slidably mounted within said drawer for pressing the staple strip in one direction, and spring means within said drawer for pressing said pusher, means on said drawer to limit the movement of the staple strip in one direction, said casing being formed with a longitudinal slot, and means on said pusher extending through said slot, said casing having a wall formed with a slot adapted to receive a driver.

3. In a stapling device, a staple magazine comprising a tubular casing, having a bottom wall, side walls, and a top wall, a drawer within said casing having a bottom wall contacting the bottom wall of the casing, and side walls contacting the side walls of said casing, and releasable means to retain a drawer within said casing, said drawer being adapted to receive a staple strip, a pusher slidably mounted within said drawer, and a spring within said drawer resting on the bottom of the drawer and adapted to press against said pusher, the top wall of the casing being

formed with a longitudinal slot, and a pin on said pusher projecting through said slot.

4. In a stapling device, a staple magazine comprising a tubular casing, having a bottom wall, side walls, and a top wall, a drawer within said casing having a bottom wall contacting the bottom wall of the casing, and side walls contacting the side walls of said casing, and releasable means to retain a drawer within said casing, said drawer being adapted to receive a staple strip, the bottom wall of the drawer and the bottom wall of the casing being formed with registering slots through which a staple may be driven, the top wall of the casing being formed with a slot disposed above the slots in said bottom walls adapted to receive a driver.

5. In a stapling device, a member immovable in a longitudinal direction and formed with a pair of aligned grooves, a drawer slidably mounted on said member and provided with flanges slideable longitudinally in said grooves, said drawer being adapted to receive a staple strip, a pusher slidably mounted within the drawer, said member being formed with a longitudinal opening, 20 said pusher having a portion projecting into said opening, and spring means within said longitudinal opening to exert resilient pressure on the pusher, said pusher being adapted to press the staple strip forwardly.

30 CHARLES B. GOODSTEIN.
